UNITED STATES PATENT OFFICE.

HANS C. HOTING, OF NEUSS, GERMANY, ASSIGNOR TO TROY LAUNDRY MACHINERY CO., LTD., OF CHICAGO, ILLINOIS, A CORPORATION OF NEW YORK.

STEAMING ATTACHMENT FOR PRESSING MACHINES.

Original application filed November 4, 1918, Serial No. 261,118. Renewed October 31, 1921, Serial No. 511,843. Patent No. 1,416,829, dated May 23, 1922. Divided and this application filed January 14, 1922. Serial No. 529,111.

To all whom it may concern:

Be it known that I, HANS C. HOTING, a citizen of the United States, residing at Neuuss, Rheinprovinz, Germany, have invented certain new and useful Improvements in Steaming Attachments for Pressing Machines, of which the following is a specification.

This invention relates to pressing machines, such, for instance, as that disclosed in my Patent No. 1,416,829, granted to me May 23, 1922, on an application filed Nov. 4, 1918, bearing Serial No. 261,118, and renewed Oct. 31, 1921, as application No. 511,843, whereof the present application is a division.

The object of the invention is to provide an improved means for delivering steam to one of the pressing members for heating the same, and also to provide a steaming attachment for supplying steam to the goods being pressed.

One feature of the invention relates particularly to the construction of the steam delivery means, and, accordingly, consists in providing the pressing member, for instance, the buck or table, with a longitudinal channel into which steam is delivered, and a cover plate for said channel fitting between the walls of the channel and embodying in its construction subdividing steam ports which insure uniform distribution of the steam throughout the length of the pressing surface, whence it permeates the fabric of the padding by which the pressing member is coated.

Another feature relates particularly to the means whereby steam may be delivered to the steaming outlet at will, and consists in providing a controllable valve for releasing steam to the steaming outlet, and locating this valve in a steam chamber which forms a part of the passage through which steam reaches the heating chamber of the pressing member, so that any water of condensation which flows back from the steaming passage will be regenerated into steam and driven off, and it will not be necessary to have any drain pipe for such water of condensation or complications for insuring sufficient pressure through the steam outlet to insure permeation of the padding.

In the preferred embodiment, the steam-

ing outlet takes its steam from the aforesaid heating chamber which surrounds its controlling valve, thus permitting a common supply pipe to serve the heating chamber of the pressing member and the steaming outlet. 55

In order that the invention will be fully understood, I will proceed to describe the same in connection with the accompanying drawing, which illustrates the preferred embodiment thereof. 60

In said drawing—

Figure 1 is a side elevation of a pressing machine in which the several features of the invention are embodied.

Figure 2 is a front view thereof.

Figure 3 is a vertical section on the line 3x—3x of Figure 1.

Figure 4 is a section on the line 4x—4x of Figure 3.

Figure 5 is a section on the line 5x—5x of Figures 3 and 4; and 75

Figure 6 is a top plan view of a portion of the steaming outlet.

10 represents the main frame carrying the support 11 for the table or buck 12, and 13 represents a support on the frame for the 80 swinging arm 14 that carries the pressing shoe 15. Arm 14 is operated to move the shoe 15 to and from the buck 12 by means which form no part of the present invention. The present invention provides means 85 for heating one of the pressing members, for instance, the buck 12, and also for releasing at will to one of the pressing members, for instance the buck 12, steam for steaming the goods being pressed. Accordingly, steam pipe 16 is made to deliver steam through pipe 17, hinging joint 18, and branch 19 to the heating chamber of the pressing shoe 15, whence water of condensation escapes through pipe 20, while a branch 21 from said pipe 16 conducts steam through the channel 22 and 23 to the heating chamber 24, 25, 26, 27, and 28 of the buck or table 12, whence water of condensation escapes through an exhaust pipe 29. And in addition to these heating means, or in addition to one of them, there is provided a valve 30 95 adapted to be operated at will by pedal 31 to deliver steam through the opening 32, pipe 33, and steam duct 34 into a channel 35 100 which is formed in the structure of the press-

105

ing member, for instance, the member 12, in order to deliver steam for steaming the goods. Channel 35 is constructed with downwardly converging walls, and it has a 5 top closure in the form of a longitudinal plate 36 fitting between its converging walls, and constructed with upwardly extending transverse grooves 37 which together with the converging walls of the channel 35 10 afford escape ducts for the spraying steam that issues from the pores of the padding over the pressing member.

In order that water of condensation flowing back through pipe 33 may be disposed of without the complication of a drain pipe which would necessitate a trap to maintain pressure at the steaming outlets 37, a collecting chamber 38 is provided at the lower end of said pipe 33, and this is so incorporated 15 in the walls of the chamber 22 that any water accumulating therein when the steaming attachment is not in use will be quickly vaporized and dissipated in the form of steam by the heat of the steam in the 20 chamber 22.

As shown more clearly in Figure 3, the chamber 38 may have an annular extension 38^a surrounding a portion of the chamber 22 to render heating effect still more efficient.

30 To facilitate construction and assembly of the parts, the valve 32 is associated with chambers 22 and 38 as the casting in which these chambers are formed affords convenient means for tapping in the several pipes 21, 23, 33, the forming of a seat for the valve 30, and the mounting of the packing gland 30^a for the stem of valve 30.

The rear end of the shoe carrying frame 40 is provided with a counterweight arm 39, to which is pivotally connected a link 40, the other end of which link is pivotally connected to a lever 41 pivoted at 42 in the frame 11 of the machine. The free end of this lever 41 is bifurcated and receives between its arms a rod 43 supporting a roller 44 and a loosely mounted cam member 45 having a flat locking face 46 to be referred to later. Pivotally connected to the rear of the frame at 47 is an operating lever 48 extending to the front of the machine, said lever resting upon the roller 44 so that when the lever 48 is depressed the bifurcated end of lever 41 will be depressed for moving the pressing shoe 15 into a pressing position, in which position the link 40 and lever 41, forming a toggle, are thrown into a line with the dead center and into engagement with an adjustable stop member 49. When the shoe is in off, or non-pressing position, the 55 toggle members comprising link 40 and lever 41 are thrown to the other side of the critical center, and the under side of a lever 50, pivotally connected at 51 to the lever 48 near the front end thereof, rides upon the loose cam 45. However, when the lever 48 is de-

pressed and the shoe 15 is moved toward a pressing position, the rear end of lever 50 gradually moves relatively to the cam locking face 46 until the straight front face 52 of the lever 50 falls from its position on top of the cam 45 down into a position engaging the locking face 46 of the cam 45, causing the pressing shoe 15 and the toggle to be locked in pressing position. This locking lever 50 will fall into a locking position 70 with respect to the locking cam 45 automatically, regardless of the variation in the thickness of the materials being pressed, for the reason that the pivotal center 51 of the locking lever 50 moves on the arc of a circle which is larger than the arc on which the center of the locking cam 45 moves. That is to say, the radius from pivotal point 47 to the pivotal point 51 of the lever 50 is greater than the radius from pivotal point 42 to the center of the locking cam 45. Accordingly, as the lever 48 is depressed, the pivotal center 51 of the locking lever 50 recedes from the center of the locking cam 45 and will continue to recede the further the 75 lever 48 is depressed, and regardless of the variation of the thickness of the material being pressed, within certain reasonable limits, the locking cam and locking lever will assume a locking relationship for holding the pressing shoe in a pressing position. To release the pressing shoe from locking position, the lever 50 is repressed, whereupon the locking face 52 thereof moves out of engagement with the locking face 46 of the cam 45, it being understood that the cam 45 is free to rotate on its support. As soon 80 as the locking lever 50 is moved out of locking position, the pressing shoe 15 will be moved upwardly out of pressing position and the toggle comprising link 40 and lever 41 will be broken as a result of the action of spring 53, one end of which is connected to an intermediate point of lever 48, the other end of which is operatively and adjustably connected to the rearwardly extending arm 85 of the shoe carrying frame 14.

I claim:

1. In a pressing machine, a pressing member having a groove in its surface forming a steam receiving channel, and a plate fitted in said groove and providing an outer wall for said channel; said plate having outwardly extending transverse grooves developing with the side walls of the groove escape ports for steam delivered to said channel.

2. In a pressing machine, a pressing member having a groove in its surface forming a steam receiving channel, and a plate fitted in said groove and providing an outer wall for said channel; said plate having outwardly extending transverse grooves developing with the side walls of the groove escape ports for steam delivered to said channel.

nel; the walls of said groove converging inwardly; and said plate having correspondingly inclined faces fitting between said walls.

- 5. In a pressing machine, pressing members, means for heating a pressing member, a conduit for supplying steam thereto, a heating chamber included in said conduit, means for releasing steam at a pressing member, a pipe leading from said heating chamber to said steam spraying means, and a trap for water of condensation returned by said pipe lying in heat absorbing relation to said heating chamber.
- 10 6. In a pressing machine, pressing members, means for heating a pressing member, a conduit for supplying steam thereto, a heating chamber included in said conduit, means for releasing steam at a pressing member, a pipe leading from said heating chamber to said steam spraying means, and a trap for water of condensation returned by said pipe lying in heat absorbing relation to said heating chamber.
- 15 7. In a pressing machine, pressing members, means for supplying heating steam to a pressing member including a heating chamber forming a part of the channel of communication for said steam, an evaporating chamber in heat-absorbing relation to said heating chamber, a valve between said chambers, a steam spraying device, and a pipe leading from said evaporating chamber to said steam spraying device.
- 20

5. In a pressing machine, pressing members, means for heating a pressing member, 25 a conduit for supplying steam thereto, a heating chamber included in said conduit, means for releasing steam at a pressing member, a pipe leading from said heating 30 chamber to said steam spraying means, and a trap for water of condensation returned by said pipe encircling a portion of said heating chamber.

6. In a pressing machine, pressing members, means for supplying heating steam to 35 a pressing member including a heating chamber forming a part of the channel of communication for said steam, an evaporating chamber encircling a portion of said 40 heating chamber, a valve between said chambers, a steam spraying device, and a pipe leading from said evaporating chamber to said steam spraying device.

Signed at Bremen, free state of Bremen, 45
Germany, this 17th day of December, 1921.

HANS C. HOTING.
